SHINGLE

Don B. Humphrey, Chicago, Ill., assignor, by
mesne assignments, to United States Gypsum
Company, Chicago, Ill., a corporation of Illinois

Application March 16, 1931, Serial No. 522,960
Renewed March 26, 1935

1 Claim. (Cl. 108—7)

The invention relates to shingles, and particularly to interlocking composition shingles, and has for its object to provide shingles of this character adapted to have an interlocking side lap with adjacent shingles whereby the nails holding the lower ends of said shingles to place are completely protected against water being laterally driven in contact therewith.

A further object is to provide a shingle of this character having an absolute interlock with its adjacent shingles on a roof whereby movement of one shingle relative to the other is effectively prevented under all conditions.

A further object is to provide a shingle of this character adapted to interlock with its adjacent shingles whereby the use of nails in laying a roof is reduced to a minimum, the interlock between the shingles holding the lower edges thereof securely to the roof.

With the above and other objects in view, the invention resides in the combination and arrangement of parts as hereinafter set forth, shown in the drawing, described, and claimed, it being understood that changes in the precise embodiment of the invention may be made within the scope of what is claimed without departing from the spirit of the invention.

In the drawing:

Figure 1 is a plan view of a roof formed of these shingles.

Figure 2 is a fragmentary perspective view of two interlocked shingles bent to expose the under side of the lower interlocked ends thereof.

Figure 3 is a plan view of the shingle.

Figure 4 is a plan view of a modified form of the shingle.

Figure 5 is a fragmentary perspective view similar to Figure 2 illustrating the interlock between shingles of the modified form shown in Figure 4.

Referring to the drawing, which illustrates the preferred embodiment of the invention, the numeral 1 designates a shingle of substantially square outline and of the composition type. At the left side of the shingle, at a point spaced from the lower edge thereof, is formed a cut 2 which may comprise a slit or a narrow cut and which extends inwardly of the side of the shingle at an angle of approximately 45 degrees toward the lower edge thereof and terminates in spaced relation to the lower edge. At the lower end of the shingle is formed a cut 3 similar to cut 2 which extends inwardly of the shingle at an angle of approximately 45 degrees in the direction of the right edge of the shingle and terminates in spaced relation to said right edge. The inner ends of

the cuts 2 and 3 extend in approximately the same horizontal plane of the shingle and are preferably equally spaced from the adjacent side edges of the shingle. Substantially triangular shaped flaps 4 and 5 are thus formed respectively by the cuts 2 and 3 at the opposite sides of the lower end of the shingle. A nail hole 6 is formed substantially centrally of the flap 5.

The shingles are laid on a roof in courses having the desired head lap 7, and the adjacent shingles in each course are given a side lap 8 in the following manner: The flap 5 is nailed to the roof through the nail hole 6 to hold the lower right side of the shingle fixed to the roof. The shingle to the right is then disposed in horizontal alignment thereto and in overlapping relation to provide the side lap 8. The flap 4 of the overlapping shingle is then passed through the cut 3 of the first-laid shingle whereby it underlays said shingle inwardly and extending upwardly of the cut 3 therein, the side lap thus provided equaling the spacing of the lower end of cut 3 from the right edge of the shingle, or twice the distance between the inner end of cut 3 from the right edge of the shingle. When so laid the cuts 2 and 3 of the overlapping and underlying shingles, respectively, are disposed at right angles to each other and oblique relative to the edges of the shingles whereby they serve to lock adjacent shingles against relative longitudinal and lateral displacement and hold the lower ends of each other effectively flat on the roof to prevent curling, loosening and the like. It will be observed that the nail which holds the flap 5 of the shingle to the roof is covered by the flap 4 of the overlapping shingle, which in turn is overlapped by the body of the underlying shingle, and therefore no water can possibly be driven under the overlapping flap 4 to the nail because of this underlapping of the end of flap 4 which overlaps the flap 5 and nail. In all previous interlocking shingles the nailed portion or flap is provided with only one overlap member whose outer edges and ends are unsecured and which will therefore be liable to curl or raise to permit water running down the roof to pass under the overlapping flap to reach the nail, which is always lower than the remainder of the shingle due to the fact that it is driven into the roof and to which lower portion the water will naturally run if it gets under the overlapping flap; and therefore in these previous shingles no adequate protection for the nail against water is provided, whereas in the instant shingle the double overlap forms an effective seal for the nail.

In Figures 4 and 5 are illustrated a modified construction of shingle in which the shingle 10 is of the same general outline as the preferred form, and in which the cut 11 and flap 13 are formed in the same manner as and correspond to the cut 7 and flap 4 of the preferred construction of the shingle. At the lower edge of this shingle and preferably spaced from the right edge thereof a distance equal to the spacing of the inner end of the cut 11 from the left edge of the shingle is formed a cut 12 formed in the same manner as cut 11 but extending parallel to the right edge of the shingle and terminating in the horizontal plane of the inner end of the cut 11 to form a rectangular flap 14 in the center of which a nail hole 15 is formed.

The modified type of shingle is laid in the same manner as the preferred type, the flap 14 being nailed to the roof and the flap 13 of the adjacent shingle passing through the cut 12 thereof and underlaying the body of the shingle. The same seal formed by the double overlap is provided by this construction as in the preferred construction, and the overlap is effective to hold the shingles in place in the same manner as the

interlock in the preferred construction. The only difference in this modified construction is in the relative angle of the cuts 11 and 12 when in interlocking relation, the angle in the modified construction somewhat facilitating the laying of the shingles.

The invention having been set forth, what is claimed as new and useful is:

A roof comprising courses of overlapping shingles, each shingle having a pair of relatively angular slits therein to form corner flaps at the opposite lower corners thereof, one slit of each shingle extending angularly downwardly from a side edge thereof and the other slit extending angularly upwardly from the lower edge of the shingle adjacent the opposite side edge thereof, the inner edges of said slits terminating in substantially horizontal alignment, a fastening passing through the lower-edge-cut flap of each shingle, said fastened flap being overlapped by an adjacent shingle whose unfastened flap underlies the body of the underlapping shingle inwardly of said fastened flap to form a watertight seal for said fastened flap.

DON B. HUMPHREY.
